Primary Examiner — Cathron Brooks*Assistant Examiner* — Sydney R Buffalow(74) Attorney, Agent, or Firm — Womble Carlyle Sandridge & Rice, LLP(57) CLAIM

We claim the ornamental design for a merchandise display tower, as shown and described.

DESCRIPTION

FIG. 1 is a front perspective view of a of a merchandise display tower including unclaimed environmental elements; and,

FIG. 2 is a front view thereof, the left, right, and rear sides appearing the same.

The broken lines shown in the drawing represent portions of the merchandise display tower that form no part of the claimed design.
